UNITED STATES PATENT OFFICE.

PEDER OLUF PEDERSEN, OF COPENHAGEN, DENMARK.

PHONOGRAPHIC APPARATUS.

SPECIFICATION forming part of Letters Patent No. 788,790, dated May 2, 1905.

Application filed August 13, 1901. Serial No. 71,910.

To all whom it may concern:

Be it known that I, PEDER OLUF PEDERSEN, a subject of the King of Denmark, residing at Copenhagen, in the Kingdom of Denmark, 5 have invented certain new and useful Improvements in Phonographic Apparatus, of which the following is a specification.

This invention relates to phonographic apparatus, and has special reference to electro-magnetic phonographs of the character described in United States Letters Patent No. 661,619, issued November 13, 1900, to Valdemar Poulsen.

The object of the invention is to provide 15 means whereby a phonograph can be conveniently used for "dictation" purposes. It is well known that all forms of mechanical phonographs are impracticable for dictation purposes because of the impossibility of making 20 corrections in the record or of quickly reproducing the dictated matter in order to ascertain at any time what has been said previously, and thus obtain the train of thought at any point where the dictation was interrupted. 25 The Poulsen invention, which is popularly known as the "telegraphone," furnishes a ready means of obliterating the record, and as the recording-electromagnet is also used for reproducing it is only necessary to provide 30 means for shifting the recording-magnet back or forth with respect to the record-surface in order to listen to what has been said or continue the dictation. The obliterating being such a simple process and also involving 35 the use of the same electromagnet, it is evident that by moving the magnet to any desired point on the record and then allowing it to traverse a portion of the record which it is desired to obliterate while the obliterating-circuit is closed this operation also becomes 40 very simple.

This invention therefore contemplates the construction of a carriage for the electromagnet, a source of electricity, transmitting and 45 receiving telephones, and an electrical switch so constructed and interconnected by circuits that by simple manipulation a person can dictate to the instrument at any speed. He can go back over any part of the already-made 50 record and listen to what he has said, and if

he wishes to make any change in the dictated matter he can obliterate any part thereof and insert, if he pleases, new matter in its place. The speech being transmitted to and from the telephone over electric circuits, the instrument itself may be located at any remote place from the person utilizing it, and all that such person needs at hand for the control and operation of the instrument is the telephone 55 transmitting and receiving instruments and a switch of the character hereinafter described.

The details of this invention will now be described with reference to the accompanying drawings, in which—

Figure 1 is a plan of a telephone fitted 65 with a portion of my improvements. Fig. 2 is a section on line xx of Fig. 1, showing the end of the telephone in side elevation. Fig. 3 is an enlarged plan of the carriage. Fig. 4 is a transverse section of the carriage. 70 Fig. 5 is a section of a detail of the carriage. Fig. 6 is a plan of the controlling-switch. Fig. 7 is a section thereof, and Fig. 8 is a diagram of the circuits.

The type of telephone here shown is 75 known as a "cylinder-machine," in which the recording body or device is in the form of a wire wound spirally upon the surface of a cylinder, the ends of the wire being mechanically secured at each end to the heads of the 80 cylinder.

In the drawings, A indicates the cylinder, and a the steel wire wound upon its surface from end to end in a single layer. This cylinder is adapted to be driven by a motor, 85 clock-train, or other suitable motive device through a belt a' , which passes around a pulley a^2 on the cylinder-shaft. The movement of the cylinder is constant and uniform when the motor is once started. The bearings of 90 the shaft of the cylinder are located in two brackets b , which extend above the upper side of the cylinder and also support a guide-rod c , which is arranged parallel and closely adjacent to the surface of the cylinder. Back 95 of this rod is also mounted in the same brackets a shaft c' , having cut or otherwise formed thereon a screw-thread of coarse pitch. On one end of this shaft is a small pulley c^2 , by means of which it is rotated, and a belt c^3 from 100

another small pulley, c^4 , on the axle of the cylinder. This belt is crossed, so that the direction of rotation of the shaft is opposite to that of the cylinder. There is also mounted 5 in the brackets b two guide rods or tracks d and d' , placed above and on each side of the rod c . The three rods c , d , and d' together constitute a guide for a carriage intended to carry the recording, reproducing, and obliterating electromagnet. This carriage is now 10 to be described with reference to Figs. 3, 4, and 5. On the rod c is a loose sleeve e , having an arm e' extending rearward under and beyond the shaft c' . At its extreme end this 15 arm carries on its under side a tooth or wedge e^2 , adapted to rest in the space between two adjacent turns of the record-wire a . On the upper side of the arm and immediately beneath the shaft c' is a lug or tooth e^3 , adapted 20 when the arm is lifted to pass between the threads on the shaft c' , but normally being out of engagement and some distance below the same. Between the lug e^3 and the sleeve arm e' carries an upright bracket e^4 , which 25 supports two electromagnets f and g , respectively. The magnet f is rigidly attached to the bracket e^4 , while the magnet g has a certain free motion with respect thereto, it being attached to a short rod g' , which passes through 30 a bearing e^5 on the bracket and projects beyond the rear thereof a short distance to receive a cross-pin g^2 . The rod g' can reciprocate in the sleeve e^5 to an extent limited by the pin g^2 at one end and the back yoke of 35 the magnet at the other. The poles of both magnets are presented forward to a block of soft iron i , forming a stationary armature, so that when the magnets are vitalized the attractive force will tend to move the magnets f and g toward the armature. The distance of movement of the magnets f and g when vitalized is such that when the magnet f is vitalized it will move toward the armature until the lug e^3 engages with the threads on the 40 rod c' , and when the magnet g is vitalized the first movement thereof toward the armature will simply draw the rod through the sleeve, leaving the bracket stationary until the pin g^2 comes against it. The further movement of the 45 magnet and until it is stopped by contact with the armature is accompanied by the bracket e^4 and arm e' : but this movement serves only to lift the wedge e^2 out of engagement with the wire a without bringing the lug e^3 into engagement with the threaded rod c' , the arm e' being 50 therefore in a mid-position. The armature is supported by the rod or tracks d d' , and for this purpose to the upper side of the armature is attached a block j of insulating material, 55 such as hard rubber, in which two axles a' have their bearings. On the extremities of the axles are placed grooved wheels a^2 , which rest on top of the said rods d d' . Thus the armature can be moved in either direction, 60 the wheels rolling upon the rods. On top of

the block j there are secured a number of metallic blocks k , k' , k^2 , k^3 , and k^4 , each of which has two binding-screws and furnishing a means to connect the various circuit-wires hereinafter referred to. To each end 70 of the armature is attached a fork i' , which extends downward and embraces the rod c , between which forks the sleeve e is confined, making a close fit therein. It will thus be seen that when the sleeve is moved along the 75 rod c the armature and its attachments, as well as the magnets, will move with it. m indicates the cylindrical incasement of the small electromagnet by which the record is impressed upon the wire, reproduced therefrom, and obliterated. This magnet being 80 of very small dimensions is embedded or incased in a cylindrical block of pitch or rubber, and only the very small pole-pieces (indicated at m') are visible. The whole device will, however, be referred to as the "magnet," and it is supported at the end of an arm o in such a position that the two poles of the magnet will straddle or ride upon one of the convolutions of the wire a . The arm o is 85 provided with two forks o' and o^2 , which pass over the sleeve e and which are therefore confined between the forks i' on the armature. To the upper side of the arm o is attached a bracket o^3 , supporting another electromagnet, 90 k , having its pole-pieces also facing the armature i , but being normally some distance therefrom, so that when the magnet is vitalized it will be attracted toward the armature and the poles of the magnet m lifted out of 95 contact with the wire a . It will now be seen that if during the rotation of the cylinder A the wedge e^2 is in contact with the wire a the whole carriage will be moved along on its 100 guide-rods by reason of the spiral arrangement of the wire a , and if the magnet m is also in contact with the wire it will also aid in this forward movement of the carriage by reason of the peculiar engagement between 105 its poles and the wire, and the whole carriage 110 will be fed along evenly and steadily because the force is applied on both sides of the guide-rod. This is the position of the parts for either recording, reproducing, or obliterating. When it is desired to stop the carriage 115 while allowing the cylinder to continue its rotation, the magnet m must be lifted out of engagement with the wire by vitalizing the magnet h , and the arm e' must be lifted to the mid-position, where it will neither engage with the 120 wire a nor the shaft c' , by vitalizing the magnet g . When it is desired to have the carriage retrace or travel backward along the guide-rods, the magnet m must be lifted out of contact with wire a , as before, and the arm e' 125 lifted until lug e^3 engages the shaft c' by vitalizing the magnet f . Since shaft c' is constantly rotating, the engagement with its threads will cause the carriage to travel backward or toward the starting-point. The switch 130

for accomplishing these movements is illustrated in Figs. 6 and 7, wherein *p* is a base, of insulating material, upon which is pivoted a double-ended metallic switch-lever *g*, one end 5 of which is adapted to engage with five different circuit-terminals, while the other end engages with two circuit-terminals. The switch-lever itself is a terminal of one circuit, while the insulated button *q*, carried by the lever, 10 is the terminal of a separate circuit, the wire to which leads through the hollow axis of the lever, as shown in Fig. 7.

The circuits will be described in connection with the operation, which is as follows: The 15 person wishing to dictate to the instrument will have on his desk or other convenient place a telephone-transmitter *T*, a telephone-receiver *R*, and a switch such as shown in Figs. 6 and 7. The telephone, with its carriage, may be located in another room or building and preferably at some place where it will not occupy valuable space, but will of course 20 be connected with the telephone through electric circuits. With the switch in the position 25 for speaking (on point 3) the motor is started in any convenient way and the dictation at once commenced. The voice-currents will traverse first the primary circuit leading from the transmitter by wire 8, through the primary winding of the induction-coil *I* to the switch-point 3, thence through the switch-lever, battery *B*, wire 9, wire 10, and wire 11 to the transmitter. The corresponding higher-tension currents induced in the secondary of 30 the induction-coil will traverse the wire 12 and recording-magnet *m*, wire 13, the insulated button in the switch, contact 6, and wire 14 to the induction-coil. The voice-currents 35 will therefore affect the magnet *m*. The current impulses flowing through magnet *m* will be recorded on the wire, because the magnet is then in contact with the wire and the carriage is traveling along the guides by reason 40 of the engagement of the magnet and the wedge *e*² with the wire, magnets *f*, *g*, and *h* being all dead. If now it is desired to stop 45 in order to compose a sentence or for any reason, the switch is thrown to the point 2. This closes the circuit from the battery by wire 9, 50 wire 10, wire 15, magnet *h*, wire 16, wire 17, magnet *g*, point 2, switch-lever, and battery. Magnets *h* and *g* being vitalized, the recording-magnet is lifted and the arm *e*' is thrown 55 to the mid-position, thus stopping the carriage. When the operator is ready to proceed, he moves the switch back to point 3 and continues as before; but if he wishes to go back and listen to all or a portion of what he 60 has already dictated he will move the switch to point 1. This will vitalize magnets *f* and *h*, as can be easily traced from the diagram, and the arm *e*' will be carried upward until it 65 engages the shaft *c*', whereupon the whole carriage will be moved back as far as desired, the operator being able to stop it at any point by

moving the switch to point 2; but if he wishes to hear what he has said he will at once move the switch to point 4 and apply the telephone-receiver to his ear. The listening-circuit will then be from the receiver by wire 10 to magnet *m*, thence by wire 13 to button *q*', to contact 7, and wire 18 to the receiver. Since the magnet is then passing over a magnetized surface, current impulses will be produced in its coils and in the circuit just traced which will correspond to the current impulses which made the record, and in consequence the listener will hear what he has previously dictated. It will be understood, of course, that when the switch is not on either of the points 70 1 and 2 the carriage will travel forward. If now the operator wishes to erase what he has just listened to or any part thereof, he will again throw the switch to point 1, leaving it there until the carriage reaches the point 75 where he began to listen or the part which he desires to erase, whereupon he will then throw the switch to point 5, which will allow a constant current from battery *d* to flow through the magnet *m* over the circuits 9, 10, and 13, 80 and the obliteration will continue as long as the switch is held in this position. The operator can then again reverse to the same point and dictate new matter to the surface 85 from which the erasure was made. The present invention does not include the indicating devices to show the position of the carriage with respect to the record; but it may be assumed that such devices can be used so that 90 the operator may ascertain at any time how much of the wire remains unused and can determine at what point along the guide the carriage is to be reversed.

Since a device for this purpose has never 95 been used heretofore in connection with mechanical or electromagnetic phonographs, the invention is not limited to any specific form of receptive surface or body, and it is also obvious that the same may be applied to a machine utilizing a band or tape of steel instead of a flat wire or to one using an extended surface of steel, such as a plain cylinder or 100 disk.

Having described my invention, I claim—

1. In a phonographic apparatus, the combination with a recording body or surface, of a carriage carrying recording, reproducing and obliterating devices, means for causing said carriage and body or surface to move forward or backward with respect to each other, or stop, and means for throwing either of said devices on the carriage into action at will. 115

2. In a phonographic apparatus, the combination of a recording body or surface, recording, reproducing and obliterating devices and 120 means whereby any one of said devices can be thrown into use when desired and the recording body or surface simultaneously moved with respect thereto.

3. In a phonographic apparatus, the combi- 125

- nation of a recording body or surface, recording, reproducing and obliterating devices adapted to coöperate therewith and movable with respect thereto, an electric switch and 5 circuits whereby the movement of the switch from point to point will determine which of said devices shall be in action and the relative motion of the active device and the recording body or surface.
- 10 4. In a phonographic apparatus, the combination of a recording body or surface, a carriage movable with respect thereto, an obliterating device on the carriage, electromagnetic devices also on the carriage and controlling 15 its relative direction of movement and a switch adapted to control said electromagnetic devices.
5. In a phonograph, the combination with the recording-surface, a carriage adapted to 20 traverse said surface, a screw-threaded shaft adapted to be engaged by said carriage, a magnet carried by the carriage, an electric circuit including said magnet and means whereby the 25 vitalizing of said magnet will cause the carriage to engage the threaded shaft.
6. In an electromagnetic phonograph, the combination with a spiral recording-surface, a screw-threaded shaft arranged parallel thereto, means for rotating the surface and the 30 shaft, a carriage carrying a recording and reproducing magnet, a device on the carriage for engaging the spiral recording-surface and another device for engaging the screw-threaded shaft, whereby the carriage is moved in 35 either of two directions, and an electromagnet adapted to disengage the carriage from the spiral surface and engage it with the screw-threaded shaft.
7. In a phonograph, the combination of a carriage adapted to carry the recording or re- 40 producing devices of two rotating spiral surfaces, an electromagnet carried by the carriage and means whereby when said magnet is energized, the carriage will be thrown out of engagement of one of said spiral surfaces and 45 into engagement with the other.
8. In a phonograph, the combination with a carriage adapted to carry the recording or reproducing devices, two spiral surfaces arranged adjacent thereto, two electromagnets 50 carried by the carriage, one of which is adapted to disengage the carriage from one of said spiral surfaces and engage it with the other, while the other magnet is adapted to disengage the carriage from one of said spiral surfaces and hold it out of engagement with both of said spiral surfaces, for the purpose set forth.
9. The combination with a phonograph and its recording and reproducing devices, of a carriage for said devices, speaking and listening instruments, and an electric switch and circuits whereby the speaking and listening instruments can be cut out and in, and the direction of movement of the carriage controlled at will. 60
